INFANT'S BIB

Robert E. Mearns, New York, N. Y.

Application August 13, 1951, Serial No. 16,259

Term of patent 7 years

(Cl. D3—26)

To all whom it may concern:

Be it known that I, Robert E. Mearns, a citizen of the United States, a resident of New York in the county of New York and State of New York, have invented a new, original, and ornamental Design for Infant's Bib, of which the following is a specification, reference being had to the accompanying drawing, forming part thereof.

I claim:

The ornamental design for an infant's bib, as shown.

ROBERT E. MEARNS.
